UNITED STATES PATENT OFFICE.

JOHN A. CLARK, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM FOR WEAVING TUFTED FABRICS.

SPECIFICATION forming part of Letters Patent No. 732,518, dated June 30, 1903.

Application filed April 11, 1903. Serial No. 152,275. (No model.)

To all whom it may concern:

Be it known that I, JOHN A. CLARK, a citizen of the United States, residing at Worcester, in the county of Worcester and State of Massachusetts, have invented certain new and useful Improvements in Looms for Weaving Tufted Fabrics, of which the following is a specification.

My invention relates to looms for weaving tufted fabrics and to that class of looms shown and described in United States Letters Patent No. 490,237, in which are employed a series of beams carried by an endless chain and having the tuft-yarns wound thereon and a series of carriages connected with said beams and provided with a series of quills or yarn-carriers for the individual tuft-yarns. The beams and carriages are taken from the chain one at a time by transferring-arms and the quills inserted into the shed to form the tufts in the well-known way and as fully described in said patent.

My invention relates more particularly to a supplemental attachment or mechanism adapted to be applied to and combined with the other parts of the loom of the class referred to, and particularly with the tuft-yarn beams and carriages carrying the quills or yarn-carriers, as will be hereinafter described.

It has been found in practice that it is very desirable to have the tuft-yarn beam and carriage carrying the quills when they reach their lowest position at the lower end of the endless chains preparatory to being removed therefrom held firmly and prevented from having any swinging motion, so that the spring-arms on the carriage, which engage a link of the endless chains to connect the carriage therewith, will be in position to be properly engaged by the releasing-fingers on the transferring-arms to allow of the disengagement of said spring-arms from the links of the endless chains and the removal of the beam and carriage from the chain by the transfer-ring-arms.

The object of my invention is to provide a simple and effective automatic mechanism for holding firmly in proper position a tuft-yarn beam and carriage when they reach their

lowest position at the lower end of the endless chain preparatory to the engagement of the transferring-arms and the removal from the endless chain of said beam and carriage.

My invention consists in certain novel features of construction of my improvements, as will be hereinafter fully described.

I have only shown in the drawings a detached portion of a loom of the class referred to and shown and described in said patent No. 490,237 with my improvements applied thereto sufficient to enable those skilled in the art to which my invention belongs to make and use the use.

Referring to the drawings, Figure 1 is an end view of a loom-frame, showing a portion of the endless chain with one tuft-yarn beam and carriage attached thereto and at its lowest position on the chain and my improvements combined therewith, the lower part of the sprocket-wheel being broken away; and Fig. 2 is a front view of the upper part of the loom shown in Fig. 1 looking in the direction of arrow *a*, same figure, and showing also the sprocket-wheels for the upper part of the endless chains carrying the tuft-yarn beams and carriages.

In the accompanying drawings, 1 is the loom-frame.

2 are hangers supported on the loom-frame and having at their lower ends journals 2' for the shaft 3, having fast on each end a sprocket-wheel 4, around which passes the lower end of the two endless chains 5, carrying a series of tuft-yarn beams 6 and carriages 7, carrying quills or tuft-yarn carriers 8, only one set of which is shown in the drawings, which are detachably connected at each end with the endless chains 5 by the spring-arms 7' in the ordinary and well-known way. The endless chains 5 at their upper ends pass over sprocket-wheels 9, fast on the shaft 10, mounted in hangers 11.

All of the above parts are of the ordinary and well-known construction and operation and fully described and shown in said Patent No. 490,237.

I will now describe my improvements, which relate only to a supplemental attachment or

mechanism for firmly holding in position the tuft-yarn beams and carriages when they reach their lowest position at the lower end of the endless chains preparatory to being ⁵ moved by the transferring-arms. (Not shown.)

On the lower ends of the hangers 2 in this instance are formed two inwardly-projecting arms or lugs 12, having pivotally attached to their ends a clamp lever or arm 13, with its ¹⁰ clamp end grooved or recessed, as shown at 13', Fig. 1, to engage the upper part of the rounded ends 6' of the tuft-yarn beam 6. A coil spiral spring 14 is confined between each supporting-arm 12 and the clamp-arm 13 and ¹⁵ acts to force down the arms 13 onto the edge of the enlarged ends 6' of the tuft-yarn beams 6. To a projection on the outer end of each clamp-arm 13 is pivotally connected the lower end of a link or connector 15. The upper end ²⁰ of each link or connector 15 is pivotally connected to a crank-arm 16, fast on a rock-shaft 17, mounted in suitable bearings 18 on the frame 1. A third crank-arm 19 is also fast on the shaft 17 and is pivotally connected, ²⁵ through a connector 20, to one end of a centrally-pivoted lever 21, pivoted to a stud 22 on the loom-frame 1. (See Fig. 1.) The other end of said lever 21 has a roll 21' thereon, which is adapted to engage the periphery of the ³⁰ cam 23, fast on the driven shaft 24, mounted in bearings 25 on the loom-frame. The spring 14, through intermediate connections, acts to hold the roll 21' on the lever 21 in engagement with the periphery of the cam 23.

³⁵ From the above description, in connection with the drawings, the operation of my improvements will be readily understood by those skilled in the art.

The periphery of the cam 23 is so shaped ⁴⁰ that through intermediate connections the clamp-levers 13 are positively raised to disengage them from the ends of the tuft-yarn beams during the revolution of the endless chains, said chains having a regular ⁴⁵ intermittent motion; but when the endless chains are stationary preparatory to the removal of the tuft-yarn beams and carriages from the endless chains by the transferring-arms (not shown) the clamp-levers 13 are moved down ⁵⁰ through the action of the springs 14 to engage the upper surface of the rounded ends of the tuft-yarn beam and hold them firmly

and prevent any movement thereof and of the carriage preparatory to the engagement of the releasing-fingers on the transferring-⁵⁵ arms with the spring-arms on the carriage.

It will be understood that the clamp-levers 13 have a spring-actuated movement to clamp and hold the ends of the tuft-yarn beams and are positively raised to allow of the free passage thereunder of the tuft-yarn beam on the movement of the endless chains and preparatory to engaging the ends of another beam.

It will be understood that the details of construction of my improvements may be varied, if desired.

I have shown two clamp-levers for the tuft-yarn beam, one at each end of the beam; but only one lever may be used at one end of the beam.

Having thus described my invention, what I claim as new, and desire to secure by Letters Patent, is—

1. In a loom for weaving tufted fabrics, the combination with the endless chains, and the tuft-yarn beams, and carriages having the quills or tuft-yarn carriers thereon, and detachably connected to the endless chains, of a clamp-lever supported above the tuft-yarn beam, and means to cause said lever to engage the enlarged end of the beam on its edge when it is in its lowest position on the lower end of the endless chains, and to cause said lever to be positively raised out of engagement with the beam, substantially as shown ⁸⁵ and described.

2. In a loom for weaving tufted fabrics, the combination with the endless chains, and the tuft-yarn beams and carriages having the quills or tuft-yarn carriers thereon, and detachably connected to the endless chains, of a clamp-lever supported above the tuft-yarn beam, and means to move down said lever to cause it to engage the edge of the enlarged end on the beam, when it is in its lowest position on the lower end of the endless chains, and means to raise said lever out of engagement with the beam, substantially as shown ⁹⁵ and described.

J. A. CLARK.
